UNITED STATES PATENT OFFICE.

CHARLES SMITH, OF CLEVELAND, OHIO, ASSIGNOR OF ONE-THIRD TO WARREN H. NOBLE,
OF CLEVELAND, OHIO.

PERMUTATION-LOCK.

No. 877,957.

Specification of Letters Patent.

Patented Feb. 4, 1908.

Application filed March 28, 1906. Serial No. 308,486.

To all whom it may concern:

Be it known that I, CHARLES SMITH, a citizen of the United States, resident of Cleveland, county of Cuyahoga, and State of Ohio, have invented a new and useful Improvement in Permutation-Locks, of which the following is a specification, the principle of the invention being herein explained and the best mode in which I have contemplated applying that principle, so as to distinguish it from other inventions.

My invention relates to permutation locks and particularly to permutation locks such as are adapted for use in combination with door-knobs.

The advantages residing in a door-knob lock are too well known to require explanation here.

The object of this present invention is to produce a lock of this type that will be simple in its construction, that may be readily substituted for the knobs of door-locks and latches at present on the market, and that will afford the greatest possible security.

To the accomplishment of these and related ends my invention consists of means hereinafter fully described and particularly set forth in the claims.

The annexed drawing and the following description set forth in detail certain mechanism embodying the invention, such disclosed means constituting but one of various mechanical forms in which the principle of the invention may be used.

In said annexed drawing: Figure 1 represents a longitudinal central cross-section of a door-knob lock embodying my invention, such lock being shown in connection with the bolt-actuating spindle and the inside knob of the ordinary door-lock or latch; Figs. 2 and 3 are views showing in enlarged size certain details of the permutation lock mechanism proper; Figs. 4 and 5 are broken perspective views of the bolt-actuating spindle; Fig. 6 is a transverse cross-section of the lock taken on the line 6—6, Fig. 1; and Fig. 7 is a development of the cylindrical surface of a serrated sleeve that forms an element of such lock.

While the principle of operation of my improved permutation lock, as will be obvious, may be readily adapted to a number of different situations, I originally devised the same for use in a door-knob lock, and I

have partly for this reason chosen this particular embodiment of my invention for the purpose of illustration and description here, without, however, meaning to imply thereby that such invention is restricted to this single practical application. As has been stated, such lock in this form is designed to replace the ordinary type of knob at present in use, without making it necessary to discard the entire latch or lock structure. Accordingly, to apply my knob-lock, all that is necessary is to replace the previous latch-actuating spindle with the spindle A shown in Fig. 1, which is of exactly the same form as the ordinary spindle although differing somewhat therefrom in structure. Such spindle, as a matter of fact, consists of two parts, *a* and *a'*, secured together end to end by means of a bolt *a*² passing lengthwise through the same. Such bolt is held in place by a suitable nut *a*³ at its threaded end which lies within the inside knob B. This inside knob B is adapted to rotate in escutcheon D, and is attached to spindle A by a set-screw *b*, in the usual manner. Outside knob C is secured, by means of the head *a*⁴ of bolt *a*², to the corresponding end of spindle A which is prolonged for this purpose some distance beyond outside escutcheon D'. The shank C' of outside knob C is fixedly mounted upon the spindle A, being held in place by means of a suitable set-screw *c* that occupies an inaccessible position within the escutcheon D' in the normal assembled condition of the parts. The knob C and its shank C' are preferably separable for convenience in putting the lock together and subsequently adjusting the same in the manner later to be set forth, but they are rigidly connected in the assembled condition just referred to.

From the construction of spindle A previously described it will be evident that ordinarily knobs B and C will be operable independently of each other, the division of the spindle being intermediately located. The portion *a* of spindle A, to which inside knob B is attached, I have extended far enough within the latch case, not shown, to engage the latch or bolt-actuating mechanism. The inside knob is thus at all times operatively connected with such mechanism. The outside knob, however, can only be thus connected therewith by first uniting the portion *a'* of spindle A, on which it is mounted, with

portion a . To effect such union any suitable, optionally-operable, clutch may be employed.

A preferred form of clutch is shown in Figs. 4 and 5; as there shown it consists simply of a reciprocatory member or bar a^5 longitudinally slidabie in such portion a' and adapted to engage a corresponding notch a^6 in the end of portion a . The mechanism whereby I am enabled to operate such member as desired constitutes the permutation lock proper which I shall now proceed to describe.

A spring a^7 , Fig. 1, located between the outer end of reciprocatory member a^5 and knob C normally urges such member a^5 forward to engage notch a^6 upon knob C being properly rotated. The action of this spring, however, and thereby the engagement of member a^5 with notch a^6 is controlled by means of a member C^2 rotatably mounted upon the part of spindle-portion a' that lies within knob C. This member C^2 is in the form of a sleeve and is most conveniently mounted upon the spindle-portion so as to be rotatable as described by being screw-threaded thereon in the manner clearly shown in Figs. 1 and 2. On its outer edge sleeve C^2 is formed with a notch c' that has a cam-surface, and reciprocatory clutch-member a^5 is provided with a lug or stud a^8 that, under the impulse of spring a^7 is at all times held against the cam-face of this notch. The form of the cam-face is such that when sleeve C^2 occupies one axial position clutch member a^5 will be entirely removed from any possibility of engagement with notch a^6 in the inside spindle portion a , while in another position such clutch member will be free to thus engage spindle portion a . Obviously no definite length need be prescribed for notch c' so long as the throw of the cam-face is sufficient to impart the necessary movement to member a^5 . Moreover, whatever the length of the notch, the cam portion should be confined to its very end in order that no forward movement of member a^5 will occur until the rotation of sleeve C^2 is complete.

To return sleeve C^2 to the first of the above positions, which I shall term its inoperative position, I form a second cam-face c^2 on its inner edge and mount in the adjacent portion of shank C' of the knob a reciprocatory pin E adapted to engage such cam-face c^2 and thereby rotate sleeve C^2 to restore stud a^8 to its original position in notch c' . For a reason that will appear later the cam-face c^2 is preferably in substantial alinement with notch c' and the position of pin E made to correspond. Such pin E bears a knob or push-button e to facilitate its operation and is provided with a spring e' that normally holds it out of engagement with the sleeve. To rotate the sleeve in the opposite direction, i. e. into its second or operative position, I employ the following permutable means.

Mounted on sleeve C^2 is a second sleeve C^3 shown by itself in Fig. 3. This sleeve is rotatable about sleeve C^2 but is normally secured against such rotation by means of a set screw c^5 , Fig. 1. Sleeve C^3 comprises an inner hollow cylindrical core c^3 , and integral therewith, or else rigidly secured thereto, an outer shell c^4 having its one edge deeply serrated. The number of serrations or teeth c^6 is not essential, but for the purpose of illustration is assumed to be eight. There are accordingly eight notches alternating therewith. These notches are of triangular form and their apexes c^8 are on a line and equidistantly spaced about the periphery of the shell, with one exception, one of the notches, the third from the left as shown in Fig. 7, having its apex to one side of the point where it would properly lie. While the apexes are thus with a single exception 85 equidistantly spaced, the teeth are not necessarily so disposed. In fact they are preferably made of distorted shape, one side being longer than the other, without regard being had to observe any particular order in 90 such arrangement; and I would, further, in the actual manufacture of my lock, seek to avoid duplication of this serrated sleeve by cutting the teeth hap-hazard without paying any attention to their conformation except 95 in the spacing of the apexes of the notches in the manner above described. The set-screw c^5 by means of which sleeve C^3 is secured to sleeve C^2 is mounted in the former sleeve adjacent to the odd-placed apex. 100 Since the notch c' is the only point about sleeve C^2 over which set screw c^5 cannot be positioned to lock the two sleeves together, it is impossible to position the odd notch over cam-face c^2 which has been described as being in substantial alinement with sleeve C^2 as said cam-notch c' .

Equidistantly spaced about the shank C' of knob C are eight longitudinally disposed grooves or slideways c^9 , one of which is occupied by pin E, already referred to as serving to restore sleeve C^2 to its initial position. The remaining seven pins E' are in all ways similar to pin E except that they are adapted to engage, not sleeve C^2 , but the serrated shell c^4 of sleeve C^3 . By reason of the disposition and shape of the notches of such shell just described, sleeve C^3 cannot be so positioned on sleeve C^2 but that some one of pins E' will, upon being pressed forward, engage the proper inclined face of a tooth of the former so as to rotate the latter towards its operative position; the odd notch is prevented, by the arrangement of notch c' , cam-face c^2 , and set-screw c^5 , from ever occupying at the beginning of the operation the blank place corresponding with pin E. It will also be clear that by successively operating the proper pins progressive rotation of sleeve C^2 will be effected until it finally reaches its operative position.

tion, whereby clutch member a^5 is permitted to unite the divided spindle A. In a lock having a given number of pins, the number that will have to be operated to accomplish this result will depend partly upon the length of cam-notch c' and the amount of rotative movement of sleeve C² made necessary thereby, and partly upon the conformation of serrations c^6 on sleeve C³. The order in which the pins E' will have to be operated will depend partly upon this conformation of the serrations, but to a larger extent upon the relative axial position of sleeve C³ upon sleeve C²; and such order is varied at any time by simply altering such relative position.

Pin E, which serves to restore sleeve C² to its inoperative position, or in other words to "lock" the door, is preferably so disposed as to be on the top or in some other definite position on the knob-shank C' when clutch member a^5 is in position to engage spindle portion a. Its button e furthermore differs in shape from the buttons e² of the other pins E' so as to be easily distinguishable therefrom by touch. By numbering it 1 and the others in order 2, 3, 4, 5, 6, 7, and 8, any given combination can be readily operated by sight; while by being able to pick out pin number 1 by its shape, one can with a little practice quickly work such combination by touch alone. To ascertain this combination, it is necessary to empirically determine it after first assembling the lock. For while it would undoubtedly be possible to adopt a standard design for serrated sleeve C³ and calculate the combinations corresponding with various designated positions of such sleeve upon clutch controlling sleeve C², this is exactly what I do not wish to do. Accordingly, as just stated, to determine the combination, I first assemble the lock, securing sleeve C³ in any position on sleeve C² that it happens to occupy or that I may choose to station it. Sleeve C² is next rotated about into its inoperative position, either directly or by means of pin E; and then the combination of pins E' necessarily operated to move sleeve C² into its operative position is found out by inspection and trial. When the lock is in place on a door it has to be removed, of course, in order to make this determination, and this can only be done by first removing the inside knob. Thus an unauthorized person would have no opportunity of making the observation described, simple as it is for one who has access to the interior of the lock. There being no plungers, tumblers, or similar parts in my lock, it is impossible for even an expert to determine by the click or sound of the moving parts whether the right combination is being allowed; pins E' operate just the same no matter in which direction sleeve E² is being rotated. It is also apparent from the haphazard manner in which it is easiest to make serrated sleeve C³ that duplicate locks are

practically impossible, while the maker has no more basis for determining the combination of the lock than the absolute novice when once the owner has adjusted it.

From the preceding description of one form of my improved permutation lock, the simplicity of its construction is at once apparent. It is also seen that as a knob-lock it may be readily applied to any of the various latches and bolts used on doors and the like without removing the same or altering their mechanism, by simply replacing the ordinary knob and spindle with the knobs and spindle shown in Fig. 1. In fact the old inside knob may be if desired retained and used as inside knob B, such knob being in no wise different from a regular door-knob. As to the efficiency of my lock, it is evident that its strength is equal to that of the latch or bolt that it is adapted to throw while its combination is so hidden from detection as to be discoverable only by chance.

Having thus described my invention in detail, that which I particularly point out and distinctly claim, is:

1. In a lock, the combination with a divided spindle, of a bar adapted to unite the same, a rotatable cam-sleeve adapted to control the operation of said bar, and permutable means for rotating said sleeve. 95

2. In a lock, the combination with a divided spindle, of a spring-actuated member adapted to unite the same, a cam adapted to control said member, and permutable means for operating said cam. 100

3. In a lock, permutable actuating means including a rotatable sleeve provided with a plurality of inclined engaging faces, and a plurality of movable members adapted to engage said inclined faces and thereby rotate 105 said sleeve.

4. In a lock, permutable actuating means including a rotatable sleeve having one end serrated; and a plurality of movable members adapted to engage the inclined faces of 110 such serrations.

5. In a lock, the combination with a movable member, of permutable actuating means therefor including a rotatable sleeve adapted to move said member, a second sleeve mounted thereon and provided with a plurality of inclined engaging faces, and a plurality of movable members adapted to engage said inclined faces and thereby rotate said sleeve. 115

6. In a lock, the combination with a movable member, of permutable actuating means therefor including a rotatable sleeve adapted to move said member, a second sleeve, having one end serrated, adjustably mounted upon said first sleeve, and a plurality of movable members adapted to engage the inclined faces of the serrations on said second sleeve. 125

7. In a lock, the combination with a divided spindle, of a bar adapted to unite the same, a rotatable cam-sleeve adapted to con- 130

trol the operation of said bar, and means for rotating said sleeve including a member connected therewith and provided with a plurality of inclined engaging faces and a plurality of movable members adapted to engage said inclined faces and thereby actuate said member to rotate said sleeve.

8. In a lock, the combination with a divided spindle, of a bar adapted to unite the same, a rotatable cam-sleeve adapted to control the operation of said bar, and means for rotating said sleeve including a member adjustably connected therewith and provided with a plurality of inclined engaging faces and a plurality of movable members adapted to engage said inclined faces and thereby actuate said member to rotate said sleeve.

9. In a lock, the combination with a divided spindle, of a reciprocatory member adapted to unite the same, a rotatable member adapted to control the reciprocation of said reciprocatory member and means for actuating said rotatable member including a cylinder mounted thereon and provided with a plurality of inclined engaging faces, and a plurality of movable members adapted to engage said inclined faces and thereby rotate said cylinder.

10. In a lock, the combination with a divided spindle, of a reciprocatory member adapted to unite the same, a rotatable member adapted to control the reciprocation of said reciprocatory member and means for actuating said rotatable member including a cylinder adjustably mounted thereon and provided with a plurality of inclined engaging faces, and a plurality of movable members adapted to engage said inclined faces and thereby rotate said cylinder.

40 11. In a lock, the combination with a di-

vided spindle, of a reciprocatory member adapted to unite the same, a rotatable member adapted to control the reciprocation of said reciprocatory member, and means for actuating said rotatable member including a sleeve mounted thereon and having its one end serrated, and a plurality of reciprocable pins adapted to engage such serrated sleeve end to rotate the same.

45 12. In a lock, the combination of a reciprocatory clutch member, a rotatable member adapted to control the reciprocation of said clutch member, and means for actuating said rotatable member including a sleeve mounted thereon and having a serrated edge, and a plurality of reciprocable pins adapted to engage such serrated edge to rotate said sleeve.

50 13. In a lock, the combination with a divided spindle, a spring-actuated member adapted to unite the same, and means for controlling the operation of said member, such means comprising a rotatable sleeve having a cam-faced notch on one edge adapted to engage said member, and a cam edge on its other end adjacent to said notch, a reciprocable pin adapted to engage such cam edge to rotate said sleeve in one direction, a second sleeve adjustably secured to said first sleeve and having a series of notches cut on its end, and a series of reciprocable pins, one 55 less in number than said notches, adapted in permutable order to engage the sides of said notches to progressively rotate said first sleeve in the opposite direction.

60 Signed by me, this 19th day of March 1906. 70

CHARLES SMITH.
